Chester A. Braselton

UNITED STATES PATENT OFFICE.

WILLIAM L. GILMORE, OF PORT WASHINGTON, NEW YORK, ASSIGNOR TO CURTISS AEROPLANE AND MOTOR CORPORATION, A CORPORATION OF NEW YORK.

AIRPLANE.

Application filed October 26, 1920. Serial No. 419,713.

To all whom it may concern:

Be it known that I, WILLIAM L. GILMORE, a citizen of the United States, residing at Port Washington, in the county of Nassau and State of New York, have invented certain new and useful Improvements in Airplanes, of which the following is a specification.

My invention relates to airplanes and is characterized principally as follows: Instead of providing, as heretofore, a distinctly separate non-lifting fuselage or body within which the motor, fuel, pilot, passenger or passengers, control mechanism, etc. are enclosed, the motor or motors herein (which ever is used) are each enclosed for the major part in separate motor nacelles. These nacelles or bodies form a composite part of the supporting surface. That is to say, as distinguished from the conventional airplane, the separate nacelles are in no sense structurally distinct bodies but are built into and along with the supporting surface as an integral part thereof. The supporting surface, (but one is used) it will be noted, is internally braced, noticeably thick and deep throughout the intermediate portion of its length and for all intents and purposes, at said intermediate portion, is of such size and cross sectional area as to completely house the various items of useful load above mentioned. Thus constructed, it is obvious that that which has heretofore added weight and resistance only, is herein made to contribute quite appreciably to the total available lift and at the same time to add but little, if any, to the total resistance of the machine considered as a whole.

For the support of the machine on water, twin pontoons are provided. These pontoons are arranged preferably substantially directly beneath the motor nacelles and with the supporting surface afford a rigid foundation for an outrigged tail structure carrying at its rear end, the empennage. Such outrigged tail structure, like the supporting surface, is markedly free from all flight resistant surfaces and in elevation is triangularly braced, the arrangement of the beams or brace members being such that maximum strength is obtained.

A further characteristic of the invention,

is the provision of cockpit space in the supporting surface, preferably intermediately between the motor nacelles and from which both motors and all control surfaces are controlled. Thus located, the various leads which extend off from the control mechanism to the control surfaces may be enclosed for the major part within the airplane wing. The supporting surface, for structural reasons, is preferably made up of separate panels, the centre panel, i. e., the intermediate portion of the supporting surface being of substantially constant cross sectional area from end to end and the outer panels of gradually decreasing cross sectional area from root to tip. In addition to the control mechanism, the fuel tank or tanks, the various instruments, and such other desirable items of useful load are wholly and entirely enclosed in the centre panel of the wing.

Of the drawings, wherein like reference numerals designate like or corresponding parts throughout the several views:

Fig. 1 is a plan view of a monoplane seaplane built in accordance with the teachings of this invention,

Fig. 2 is a side elevation of the machine illustrated in Fig. 1, and

Fig. 3 is a front elevation (the supporting surface being partly broken away).

Before proceeding with a detail description of the machine, it is to be understood that I do not limit myself to a given or specific type of machine. The drawings illustrate a twin float monoplane seaplane. Obviously, however, a land machine might easily be constructed along the lines of the machine herein illustrated without departing from the spirit of the invention as hereinafter claimed.

For structural reasons, the supporting surface, the full span of which is illustrated in Fig. 1 is made up of separate panels. Said surface, designated as an entirety as 10 and in the embodiment of the invention herein selected for illustration, comprises a centre panel 11 and outer or main panels 12-12. The centre panel from end to end is of substantially constant cross sectional area and compared with machines of conventional design is extraordinarily thick and

deep. The outer panels 12—12 are directly fastened to the ends of the centre panel and from the root laterally gradually decrease in cross sectional area, the top of the supporting surface from tip to tip viewed from either the front or rear, defining a straight line, though in cross section being heavily cambered. The underneath surface, unlike the top surface is substantially horizontally flat from end to end of the centre panel 11 and correspondingly flat though upwardly inclined from the ends of the centre panel laterally. Such construction provides in effect a noticeable dihedral angle and admits of a rigid construction without the necessity of any external bracing whatsoever. Lateral balance of the machine is obtained through manipulation of ailerons 13—13 which are adapted to be operated in the usual way.

At or near the ends of the centre panel 11 and built thereinto as an integral part thereof, are symmetrically arranged motor nacelles 14—14. These nacelles, (see Fig. 1) slightly overhang the leading edge of the supporting surface and terminate rearwardly at points somewhat in advance of the trailing edge. In the construction of the centre panel, the engine bed beams (not shown) and the framework of the motor nacelles, are made as an integral part of the framework of the centre panel and they are not, as has been the practice heretofore, made detachable and as distinctly separate bodies. In each motor nacelles, a motor 15 is enclosed.

Intermediately between the motor nacelles 14—14, cockpit space is provided. Such space (see Fig. 1) is designated herein as 16 and as indicated is confined for the major part to the centre panel of the supporting surface. Thus arranged the use of a distinctly separate non-lifting body for the housing of the occupants is avoided.

Beneath the centre panel and preferably substantially beneath the motor nacelles 14—14 twin pontoons 17—17 are arranged. These pontoons (see Figs. 2 and 3) are more or less of conventional design. If desired, a landing gear suitable for land operation may be substituted for the pontoons.

Spaced longitudinally aft of the trailing edge of the intermediate panel 11 is the empennage 18 of the craft. Such empennage includes a vertical rudder 19, elevator flaps 20, vertical stabilizer 21 and horizontal stabilizer 22. As a support for the empennage an outrigger tail structure carried jointly by the pontoons and the supporting surface, is used. Such tail structure includes upper parallel beams or outriggers 23 and lower upwardly inclined parallel beams or outriggers 24, the former being extended straight back from vertical fin surfaces 25 projected above the top surface of the centre panel 11 in rearward continua-

tion of the motor nacelles, and the latter (the beams 24) upwardly and rearwardly from the stern end of each pontoon. In line with the trailing edge of the center panel, the beams 23 and 24 are interbraced as at 70 26, such interbracing completing a triangulated system of bracing best illustrated in Fig. 2.

In addition to housing the occupants of the machine within the confines of the supporting surface, the fuel tank or tanks (not shown), the control mechanism (not shown), and such other items of useful load, are likewise thus confined. This is true to a considerable extent also of the motor nacelles 80 since the generating lines of the nacelle bodies if carried out, would extend deep into the supporting surface. The advantage in thus arranging the various components inside the supporting surface, is obvious. As intimated, that which has heretofore resulted in detrimental resistance only as herein arranged increases the useful lift. For a full understanding, however, of that which is considered new and novel, reference should be had to the appended claims.

What is claimed is:

1. In an airplane, a supporting surface, a motor, a motor nacelle formed as a composite part of the supporting surface, an 95 empennage spaced longitudinally aft of the trailing edge of the supporting surface, cockpit space formed in the supporting surface, a landing gear, and an outrigger tail structure carried jointly by the landing gear 100 and supporting surface to support the empennage.

2. In an airplane, a supporting surface, two motors, a nacelle for each motor formed as a composite part of the supporting surface, an empennage spaced longitudinally aft of the trailing edge of the supporting surface, cockpit space formed in the supporting surface intermediately between the motor nacelles, a landing gear, and an outrigger tail structure carried jointly by the landing gear and supporting surface to support the empennage.

3. In an airplane, a supporting surface of substantially constant cross sectional area throughout the intermediate portion of its length and of gradually decreasing cross sectional area from the ends of said intermediate portion outwardly toward the wing tips, a motor, separate motor nacelles formed 115 as a composite part of the intermediate portion of the supporting surface, an empennage spaced longitudinally aft of the trailing edge of the supporting surface, cockpit space formed in the intermediate portion 120 of the supporting surface, a landing gear, and an outrigger tail structure comprising beams extending rearwardly from the supporting surface substantially in prolongation of the two motor nacelles.

4. In an airplane, a supporting surface of substantially constant cross sectional area throughout the intermediate portion of its length and of gradually decreasing cross sectional area from the ends of said intermediate portion outwardly toward the wing tips, two motors, a nacelle for each motor formed as a composite part of the intermediate portion of the supporting surface, cockpit space formed in the supporting surface intermediately between the motor nacelles, an empennage spaced longitudinally aft of the trailing edge of the supporting surface, a landing gear, and an outriggered tail structure comprising beams extending rearwardly from both the supporting surface and from the landing gear.

5. In an airplane, a supporting surface, two motors, a nacelle for each motor formed as a composite part of the supporting surface, an empennage spaced longitudinally aft of the trailing edge of the supporting surface, a landing gear including spaced landing devices arranged respectively substantially directly beneath the motor nacelles and an outriggered tail structure carried jointly by the landing gear and supporting surface to support the empennage.

6. In an airplane, a supporting surface, a motor, a motor nacelle formed as a composite part of the supporting surface, an empennage spaced longitudinally aft of the trailing edge of the supporting surface, a landing gear, and a supporting tail structure for the empennage comprising beams carried respectively by the landing gear and supporting surface.

7. In an airplane, a supporting surface of substantially constant cross sectional area throughout the intermediate portion of its length and of gradually decreasing cross sectional area from the ends of said intermediate portion outwardly toward the wing tips, a motor, a motor nacelle formed as a composite part of the intermediate portion of the supporting surface, cockpit space formed in the intermediate portion of the supporting surface, an empennage spaced longitudinally aft of the trailing edge of the supporting surface, a landing gear arranged beneath the intermediate portion of the supporting surface, and a supporting tail structure for the empennage comprising beams carried respectively by the landing gear and intermediate portion of the supporting surface.

8. In a monoplane, a divided supporting surface comprising a centre panel of substantially constant cross sectional area from end to end and outer panels of gradually decreasing cross sectional area from root to tip, a motor, cockpit space formed in the centre panel of the supporting surface, a landing gear, an empennage spaced longitudinally aft of the trailing edge of the sup-

porting surface, and a supporting tail structure for the empennage including beams extended rearwardly from the centre panel respectively at opposite sides of the cockpit and from the landing gear.

9. In a monoplane, a divided supporting surface comprising a centre panel of substantially constant cross sectional area from end to end, and outer panels of gradually decreasing cross sectional area from root to tip, two motors, a nacelle for each motor, each nacelle being formed as a composite part of the centre panel of the supporting surface, cockpit space formed in the supporting surface intermediately between the motor nacelles, an empennage spaced longitudinally aft of the trailing edge of the centre panel, and a supporting tail structure for the empennage including beams extending back from the centre panel substantially in prolongation of the spaced motor nacelles.

10. In a monoplane seaplane, a supporting surface, cockpit space formed in the supporting surface, motors arranged respectively at opposite sides of the cockpit space, each motor being substantially enclosed in a motor nacelle formed as a composite part of the supporting surface, pontoons mounted respectively directly beneath the motor nacelles, an empennage spaced longitudinally aft of the trailing edge of the supporting surface, and a supporting tail structure for the empennage including four beams, two of which are carried by the supporting surface and the other two respectively by the pontoons.

11. In an airplane, a supporting surface, cockpit space formed in the supporting surface, motors arranged respectively at opposite sides of the cockpit space, each motor being substantially enclosed in a motor nacelle constructed as a composite part of the supporting surface, landing devices disposed substantially directly beneath the motor nacelles, an empennage spaced longitudinally aft of the trailing edge of the supporting surface, and an outriggered tail structure for the empennage carried jointly by the landing device and the supporting surface.

12. In an airplane, a supporting surface, a motor enclosed for the major part within a motor nacelle formed as a composite part of the supporting surface, cockpit space formed in the supporting surface, a landing device mounted substantially directly beneath the motor nacelle, and an outriggered tail structure comprising an empennage and a support therefor carried jointly by the landing device and the supporting surface.

13. In an airplane, a supporting surface, cockpit space formed in the supporting surface, motors enclosed for the major part in nacelles formed as a composite part of the supporting surface, the arrangement of the motors with respect to the cockpit space be-

ing such that the latter is intermediately located between the motor nacelles, an empennage spaced longitudinally aft of the trailing edge of the supporting surface, a landing gear including spaced pontoons disposed substantially directly beneath the motor nacelles, and a support for the empennage com-

prising beams projected rearwardly respectively from each motor nacelle and from each pontoon.

10

In testimony whereof I hereunto affix my signature.

WILLIAM L. GILMORE.
